**ROTARY MARKING TOOL FOR USE IN SCREW
MACHINES OR THE LIKE**
William R. King, Wilkinsburg, and Joseph C. Lang, Pittsburgh, Pa., assignors to Jas. H. Mathews & Company, Pittsburgh, Pa., a corporation of Pennsylvania
Filed Aug. 9, 1962, Ser. No. 215,843
6 Claims. (Cl. 101—7)

This invention relates generally to a rotary marker, and, more particularly, to a rotary marker having a wheel with type embossed on its periphery for marking a code or other information on an article.

In the marking of hard materials such as wood, metal, and certain plastics, it is the practice to press type into the surface of the material by markers, punches, and the like. Articles manufactured by lathes or screw machines, for example, are marked during the final stages of the product manufacturing operation, and it is in this environment that the present invention is especially applicable. Usually articles so marked are relatively small pieces made in rapid succession, and therefore are rotated at relatively high speed in the machine in which they are formed. As the article is being rotated by the machine, a marker wheel is brought into contact with the rotating article which causes the wheel to rotate in the opposite direction not unlike the engagement of friction wheels or gears with one another, but for less than one complete rotation of the marking wheel. The raised or embossed type on the marker wheel are thus pressed into the surface of the piece with which it is engaged. After the piece is marked, it is necessary for the marker wheel to be stopped and held against rotation in either direction and then to be backed away from the article and to be rotated in the direction opposite of that when marking is achieved in order that the wheel will return to its original position for marking the next piece.

Markers of the nature of the present invention which are known in the art engage the surface of a rotating workpiece on a machine and impress marks therein.

However, proper sustained operation of such markers to give uniformly clear markings in rapid succession has been difficult to accomplish due to the marking wheel turning too freely in the initial period of contact with the work piece and then, having built up a considerable inertia, being stopped too abruptly.

A further difficulty with existing markers of this character with which I am familiar arises from the spring arrangement for returning the marking wheel to starting position when the brake is released. Space limitations are such that the tension springs employed for this purpose were flexed so far in proportion to their lengths as to materially reduce their useful life.

According to the present invention, the concept is advanced of braking a marker wheel throughout its rotation with a progressively greater force being applied as the wheel rotates, and finally terminating the rotation of the wheel in less than a full revolution from the start of the marking operation whereby a smooth or steady pressure without slippage or erratic rotation is maintained by the wheel against the article to clearly mark the article by the type on the wheel. The present invention is designed such that a long wheel return spring is provided which serves both to return the wheel to its starting position and to apply a progressively greater force on a wheel brake as the spring is tensioned by rotation of the marking wheel in the reverse direction from the starting position through the marking cycle.

It is a principal object of this invention to provide a new and improved rotary marker of the type referred to.

Another important object of the invention is to provide

2

a rotary marker for use in screw machines and the like wherein the wheel return spring and the brake are interconnected in such manner as to enable a long spring to be used and the pressure of the brake to become increasingly effective as the marker wheel rotates through its cycle.

A further object of the invention is to provide in a marking tool of this character an improved marking wheel brake in which braking is effected by combining the rectilinear and transverse movements of the braking member.

10 A still further object is to provide a unique tool assembly in which replacement of the marking wheel is readily accomplished.

15 A complete understanding of the invention may be had from the following detailed description of a specific embodiment thereof when read in conjunction with the appended drawings, wherein:

FIG. 1 shows a plan view of a preferred embodiment of the invention;

FIG. 2 illustrates a front elevation of the apparatus 20 shown in FIG. 1;

FIG. 3 is a side elevation of the apparatus shown in FIG. 2;

FIG. 4 shows a fragmentary isometric view of the friction brake and brake release lever;

25 FIG. 5 is an exploded isometric view of the marking wheel holder with the marking wheel shaft and associated parts removed, and with parts separated from their normal position to better show the construction;

FIG. 6 is a transverse section in the plane of line VI—VI 30 of FIG. 1, but on a larger scale; and

FIG. 7 is a fragmentary view taken at right angles through the upper portion of FIG. 6, the section being in the plane of line VII—VII of FIG. 1.

Referring now to the drawings, wherein like reference 35 characters designate like or corresponding parts throughout the several views, there is shown in FIG. 1 a marker generally designated numeral 11. The marker 11 is releasably attached to a shank 12 which is shaped to be received firmly by a tool holder, not shown, of a machine 40 which operates to rotate an article such as a screw to be machined and marked for example.

The head 13 of the marker 11 is bifurcated to form two parallel spaced arms 14 and 15, each of which are provided with bearings 16 which are axially aligned. Journaled in the bearings 16 for rotation is a shaft 17 to which is keyed a marking wheel 18 having raised marking characters 19 on its periphery and extending through an arc less than the wheel circumference and as shown in the drawing there are sloping cam-like surfaces leading up to and away from these characters as is customary in marking wheels for this purpose. The wheel 18 has a laterally-extending hub portion 21 so that the wheel with its hub has only a rotating clearance between the arms 14 and 15. As shown best in FIG. 1 the wheel 18 is of a diameter to 50 extend past the ends 22 of the arms 14 and 15 whereupon the type 19 travels in a path to freely contact an article to be marked.

The shaft 17 extends laterally beyond the arm 15, and the portion 23 of the shaft next to the arm 15 is of greater 55 diameter than the part on which the marking wheel is carried. The peripheral surface 24 of the portion 23 has a smooth finish which is hardened to function as a brake surface and part 23—24 constitutes a brake drum. A circular wheel element 25 is formed integrally with the shaft portion 23 or fixed thereto by suitable means, not shown, and the periphery of this wheel element is provided with an annular groove 26. There is therefore provided in the holder a rotatable assembly comprising shaft 17, marking wheel 18, brake drum 23—24, and a second wheel or second wheel element 25.

The shaft 17 is removably contained for rotation within

the bearings 16 by an elongated pin 27 which passes through the bearing in the arm 14 tangentially of the shaft and between the walls of a circumferential groove 28 in the shaft 17 within the bearing. The pin 27 extends vertically above the arm 14 and is bent on itself to provide a crook 29 with the end of the crook being received within a bore 31 extending into the arm 14 to restrain the pin from rotation about its axis. By means of the pin 27 engagement with the recess 28 the shaft is prevented from movement in an axial direction, but the shaft is free to rotate.

To replace the wheel 18 with another, the pin 27 is grasped by the crook 29 and pulled vertically from the marker 11. The shaft 17 is then slid sidewise toward the arm 15 by pulling the wheel element 25 in such direction. When the marking wheel 18 slips off the end of the shaft, another wheel may then be slipped onto the shaft end by aligning its keyway with the key on the shaft. Then the wheel element 25 is urged toward the arm 15 which action carries the end of the shaft 17 toward the arm 14 to be seated within the bearing 16 and locked against further axial movement by passage of the pin 27 between the walls of the shaft annular recess 28.

The wheel element 25 has a tapped opening in its periphery within which is received a headed fastener 32. One end of a flexible coiled tension spring 33 is held firmly beneath the head of the fastener 32, and the spring passes around the grooved periphery of a fixed arcuate support or spring guide 34 which is aligned with the member 25. The support 34 is fixed by screw 35 on a bifurcated brake-guide frame 36, FIGS. 1 and 2, secured to the marker head 13 by fasteners such as screws 37, and the frame 36 is provided with a guideway 38 having a lower surface which slopes downwardly towards its open end 39 to a horizontal plane below the horizontal plane of the axis of rotation of the shaft 17. Disposed in the closed opposite end 41 of the guideway 38 are resilient packings or cushion 42.

A brake 43 is slidably mounted in the guideway 38 of the frame 36 for rectilinear movement therein, and is of a vertical dimension such that its projecting end or nose 44 will move in a rocking motion transversely of its length by reason of the slope of the guideway which provides a vertical clearance or tolerance between the guideway upper and lower walls and the brake 43 guided therebetween. The nose 44 is shaped to establish a line contact with the braking surface 24 of the cylindrical braking drum portion 23 of the shaft 17 against which it is urged by the resilient packing or cushion 42 within the guideway end 41.

The other end of the tension spring 33 is attached to a boss 45 extending from the exposed section of the brake 43 protruding from the open end 39 of the guideway 38. Inasmuch as the spring is passed about the grooved guide 34, the force of the spring urges the brake 43 downwardly at its end or nose 44, thus pulling the nose below the plane which includes the axis of rotation of the shaft 17 and brake drum 23.

A vertically extending passageway 46 in the frame 36 is in alignment with a slot 47 in the brake 43 within the guideway 38 into which a brake release lever 48 is guidingly received. The lever 48 is pinned to a stud 49 fixed to the frame within the passageway 46 such that the lever pivots about the stud. The lever has an elongated opening 51 extending through the end portion thereof, which is positioned within the guideway slot 47, through which is received a pin 52 which is fixed to the brake 43 and which protrudes into the guideway 38 laterally. As shown in FIG. 2, the width of the passageway 46 is greater than the width of the slot 47 such that the lever 48 when pivoted about the stud 49 moves the brake 43 axially within the guideway 38. The elongated opening 51 provided in the lever 48 permits the brake 43 to move vertically to effect a rocking motion at the nose 44. Ac-

cordingly, pushing the lever 48 to the right as viewed in FIG. 2 will retract the contact of the nose 44 with the braking surface 24 of the circular member 25.

A stop member 53 extends from the brake surface 24 of the shaft 17 and is adjustably retained within a bore 54 passed radially into the shaft, FIG. 2, and the stop member abuts a shoulder 55 on the frame 36 limiting the rotation of the circular member 25 in a counter-clockwise direction.

Operation

The marker 11 is advanced by a machine tool holder in which the shank of the marker is held against the surface of a rotating article to be marked when the marker is in a rest or start position as depicted in FIGS. 1 and 2. When the periphery of the marker wheel 18, which as explained is slightly eccentric as shown in FIG. 2, engages the rotating article, the latter turns the marker wheel and its shaft 18 clockwise. The brake nose 44, which is urged normally into contact with the brake drum 24 by the resilient packing or cushion 42, is carried over center by the rotation of a brake drum 24 from its rest position below the center of rotation of the shaft 17 to a position above the center. The tension spring 33 wraps about the return spring wheel 25 as the shaft rotates and exerts an increasing force to urge the brake down against the drum by reason of its attachment at 45 to the brake member. The type 19 is carried by rotation of the type wheel into impressing contact with the surface of the article, imprinting the desired code into the article surface. After the marking is completed the article engages the arc of the wheel which is shown in the upper side of the type in FIG. 2. By the time the type wheel has rotated far enough that the eccentric surface beyond the type has cleared the work piece, the brake will check further rotation of the rotating parts under their own inertia and the type wheel will be stopped with its surface clear of the work piece. The work piece may therefore continue to rotate as it may do many times before it is carried away from the marking station.

The force of the spring 33 continues to hold the member 25 against retrograde or counter-clockwise rotation until the brake is released by pushing the lever 48 to the right as viewed in FIG. 2 to retract the brake nose 44 slightly and compress the cushion 42. When the brake is released, spring 33, exerting a pull on the spring return wheel 25, rotates this wheel and shaft 17 and the marking wheel counterclockwise back to the start position. This reverse rotation is stopped while the spring is still under slight tension when member 53 strikes shoulder 55 of the frame 36. The lever 48 is tripped upon withdrawal of the entire marker 11 from engagement with the rotating article. The marking operation is repeated on an article subsequently rotated by a machine when the wheel 18 is pressed into engagement with the article. The marking wheel 18 by the operation explained hereinabove engages the article or workpiece during only one rotation of the workpiece, but the wheel never completes a full revolution.

It is manifest that the above-described embodiment of the invention is merely illustrative and that numerous modifications may be made within the spirit and scope of the invention. Further, it will be understood that the rotation of a workpiece is given as an example only for the reason that the article may be stationary and the marker may rotate on the article by moving the entire marker by a suitable means, it being necessary only that relative rotation between the article and the marker wheel periphery is effected in order to achieve the marking of an article.

We claim:

1. A rotary marker comprising a bifurcated head with spaced parallel arms having aligned bearings, a shaft journaled in the bearings and bridging the spacing be-

tween the arms, a marking wheel having type on the periphery thereof mounted on the shaft between the arms for rotation with the shaft, the shaft extending laterally beyond one of the arms and having a circumferential braking surface beyond the arm, a circular member with a grooved periphery fixed to the end of the shaft adjacent the braking surface for simultaneous rotation with the shaft and wheel, a frame secured to the head, an arcuate support with a grooved periphery mounted fixedly on the frame with the groove in alignment with the grooved periphery of the circular member, the frame having a horizontally extending guideway, a brake slidably mounted within the guideway with a nose formed for line contact with the braking surface, resilient means within the guideway for biasing the brake nose into line contact with the braking surface of the shaft, the brake having a vertically extending slot, the frame having a vertically extending passageway in alignment with the slot in the brake, a brake release lever pivoted within the passageway and pinned to the brake within the slot for moving the brake slidably within the guideway, a spring fixed at one end to the periphery of the circular member and extending around the grooved periphery of the arcuate support, the other end of the spring being attached to the brake portion extending from the guideway whereby a force is exerted downwardly on the nose of the brake against the braking surface, the guideway being of a dimension whereby the nose of the brake rocks from below the axis of the circular member to a point above the axis of the circular member, a stop member extending from the periphery of the circular member for limiting its rotation and being in abutting contact with the frame at a position of rest from which the wheel rotates in a marking operation, the rotation of the circular member increasing the tension on the spring whereby the nose of the brake is pulled downwardly with increasing force against the braking surface of the shaft in proportion to the amount of rotation of the circular member whereby the circular member is stopped by the brake after the type on the wheel have marked an article, the release of the brake by the lever actuating a retrograde rotation of the circular member by the action of the spring.

2. In a marking tool of the character having a holder of the type having a marker wheel adapted to be rotated in one direction by engagement with a rotary work piece in one direction and a second wheel fixed to rotate with the marking wheel and having a tension spring that is wrapped by rotation of the marking wheel about the periphery of the second wheel, the spring having one end anchored to the periphery of the second wheel whereby it will wrap about the periphery of said second wheel when said wheel is rotated in one direction and effect rotation of the second wheel in the opposite direction to return the said wheel to starting position, wherein

- (a) there is a brake drum also arranged to rotate with the marking wheel and the second wheel,
- (b) a brake bar having a nose bearing against the brake drum,
- (c) the brake bar being supported on the holder in a manner to enable the nose to travel through a limited arc transversely of the length of the bar and also move rectilinearly relative to the brake drum,
- (d) means for resiliently urging the nose of the brake bar against the brake drum,
- (e) the spring having its other end anchored to the brake bar and guided about the holder in such manner that the tensioning of the spring as it wraps about the second wheel increases the pressure of the nose of the brake bar against the drum.

3. A marking tool of the class described comprising

- (a) a holder,
- (b) a marking wheel shaft in the holder,
- (c) a marking wheel, a brake drum, and a spring re-

5

turn wheel fixed on the shaft for rotation with the shaft,

- (d) a brake bar holding means on the holder,
- (e) a brake bar in the holding means having a nose bearing against the brake drum, the brake bar being axially movable in the holding means and also movable transversely of its length with the nose moving in an arc from a position where the nose is in a plane below the axis of rotation of the marking wheel shaft over center to a plane above said axis,
- (f) means for resiliently urging the brake bar nose against the brake drum,
- (g) a spring attached to the brake bar near the nose extending downwardly from the bar,
- (h) guide means on the holder about which the spring is looped so that after extending downwardly from the bar it extends rearwardly, upwardly and then forwardly at a level above the bar,
- (i) the other end of the spring being attached to the spring return wheel in a manner to wrap about the periphery of said wheel when it is rotated in one direction against the tension of the spring.

4. A marking tool as defined in claim 3 wherein a brake release lever is pivotally mounted between its ends on the holder with one end projecting above the holder and having its other end passing transversely through the brake bar intermediate its ends, whereby movement of the lever imparts rectilinear movement to the brake bar, the engagement of the lever with the brake bar being such as to allow transverse movement of the brake bar relative to the lever.

5. A marking tool of the character described comprising a holder, a rotatable shaft in the holder, a marking wheel, brake drum and return spring wheel all fixed to the shaft for rotation therewith, the periphery of the marker wheel extending beyond the holder and being of greater diameter than the brake drum and return spring wheel, a brake bar having a nose portion bearing against the brake drum and movable rectilinearly transversely with respect to the axis of rotation of the shaft with the nose portion of the bar being movable transversely relative to said axis, guide means on the holder in which the brake bar is retained for such movement, resilient cushion means between the guide means and the brake bar for resiliently urging the bar rectilinearly toward the brake drum, an extensible flexible spring having one end attached to the return spring wheel and its other end attached to the brake bar near the nose thereof, a spring looping guide on the holder, the spring extending from its point of attachment to the brake bar transversely to the length of the bar, thence around the guide and looping forwardly in a direction generally parallel with the bar to the spring return wheel, and a trip lever engaging the brake bar for effecting rectilinear movement of the brake bar to release the brake bar from braking engagement with the drum.

6. A marking tool as defined in claim 3 wherein the marking wheel is keyed to the shaft, the holder having two arms through which the shaft passes with the marking wheel positioned between these arms, the brake drum and spring return wheel being on one end of the shaft outside the space between the two arms, and removable means in the other arm interfitting with the shaft to permit rotation thereof, said shaft being movable endwise upon removal of said last-named means to enable the marker wheel to be removed and replaced.
